UNITED STATES PATENT OFFICE.

NATHAN H. SUREN, OF NEEDHAM, MASSACHUSETTS, ASSIGNOR TO GAMEWELL FIRE ALARM TELEGRAPH COMPANY, OF NEW YORK, N. Y., A CORPORATION OF NEW YORK.

RELAY.

1,145,940.

Specification of Letters Patent. Patented Ju'y 13, 1915.

Application filed February 10, 1913. Serial No. 747,322.

To all whom it may concern:

Be it known that I, NATHAN H. SUREN, a citizen of the United States, residing at Needham, in the county of Norfolk and 5 State of Massachusetts, have invented an Improvement in Relays, of which the following is a specification.

This invention relates to an improvement in relays adapted for use in signaling systems.

The object of the invention is to provide a relay especially adapted for use in controlling the circuit of an electrically operated whistle, horn, signal-recorder and 15 other devices employed for fire-alarm and other signals, by which the blasts of the whistle and horn and the dashes of the signal-recorder will have a predetermined and uniform length, irrespective of the duration 20 of the long breaks of the controlling-circuit produced by the signal-transmitter or any other cause, and the blasts of the whistle, horn and dashes of the recorder will be of a length corresponding with the duration 25 of the short breaks of the controlling-circuit produced by the signal-transmitter or any other cause. Thus a single relay embodying this invention may be employed to control one or more local circuits, each containing one or more signal-receiving instruments of any of the well known or suitable forms.

In carrying out my invention I employ an electro-magnet as a relay-magnet, which 35 is adapted to respond to the makes and breaks of a controlling-circuit, having an armature for controlling the movement of a movable contact-member in one direction and a timed actuating-device associated 40 therewith for controlling the movement of said contact-member in another direction, said movable contact-member being adapted for coöperation with a stationary contact-member or members for controlling one or 45 more relay-circuits which control the operation of a whistle, horn, signal-recording and other signal-responding and signal-receiving instruments. The timed actuating-device is set in condition to operate by a 50 movement of the armature. In case the relay-magnet is arranged in a closed circuit it will become deenergized upon a break in said circuit, and upon retraction of its armature the movable contact-member will be 55 moved immediately into engagement with

the stationary contact-members, thereby closing the relay-circuits, and the timed actuating-device will be set in condition to operate, and will immediately thereafter begin to move said movable contact-member out of engagement with said stationary contact-member, and in case the break in said circuit is of long duration will complete such movement at the end of a predetermined period of time, thereby insuring a 60 closure of the relay-circuit for a predetermined length of time in response to a break of as long or longer duration than said predetermined length of time; and in case the break in said circuit is of short duration 65 such movement of the timed actuating-device will not be completed before it is returned to normal position upon attraction of the relay-armature, thereby insuring a closure of the relay-circuit of a length corresponding with the length of the short break in the controlling-circuit. 75

For simplicity of construction I employ the retractile-spring for the armature as the actuating-spring for the timed actuating-device. 80

In the accompanying drawing, Figure 1 is a side elevation of an illustrative embodiment of the invention, with the parts in normal position. Fig. 2 is a plan view of the 85 same. Fig. 3 is a vertical section taken on the line 3—3, in Fig. 1. Fig. 4 is a fragmentary side elevation showing the position of the parts at the moment when the circuit through the relay is broken and the contact-members are moved into engagement, and, Fig. 5 is a similar view showing the position of the parts when the contact-members are separated by the actuation of the 90 spring, the circuit through the relay being 95 still broken.

As illustrated in the drawing, 10 represents a pair of electromagnet-coils which are electrically connected together and to binding-posts 12, 14, mounted upon an insulating base 15, and any usual or suitable form of signal-transmitter is or may be employed for controlling a signaling-circuit which is connected to said binding-posts 12 and 14. 100 An armature 16 coöperates with the coils 10, and is carried by an arm 18, fast upon a pivot-shaft 20, journaled in conical recesses formed in screws 22 threaded through ears 24 provided at the opposite ends of a plate 26, said plate being mounted upon the upper 110

ends of the coils 10, or otherwise supported. Depending from the shaft 20 is an arm 28, which is bifurcated at its lower portion and carries a transverse bar 30. The bar 30 is provided at each end with a sleeve 31, 32, insulated therefrom by an insulating bushing 34, said sleeves carrying platinum contact-strips 35, 36, respectively. The bar 30 with its contacts constitutes the movable contact-member. As here shown the contact-strip 35 is adapted to engage stationary contact-members 38, 39, and the contact-strip 36 is adapted to engage stationary contact-members 40, 41, mounted upon the base 15. The members 39 and 41 are connected with binding-posts 44 and 45, respectively, and the members 38 and 40 are connected to binding-posts 46 and 48, by conductors 49, 50, respectively, passing along the under side 20 of the base 15. Thus, as here shown, said movable contact-member is arranged to control two local or relay-circuits, but any other number of local or relay-circuits may be controlled by it, as may be required. A retractile spring 52 is connected at its upper end to a screw 54, which projects laterally from the upper end of the arm 28, and also acts as a regulating adjustment by lengthening and shortening, and the lower end of 30 said spring is connected to an ear 56, which projects laterally from a lever 58, fulcrumed in a slotted post 60 mounted upon a ledge 62, which projects upwardly from the base 15. When the magnet-coils 10 are energized, as shown in Fig. 1, the armature 16 is attracted, and the movable contact-member 30 is swung away from the stationary contact-members, and the spring 52 is placed under tension. When the magnet-coils 10 are deenergized, 40 the armature 16 is permitted to retract under the action of the spring 52, and the arm 28 with its transverse bar 30 and contact-members is swung inward, so that the contact-strips or members 35, 36 engage their co-operating stationary contact-members, 38, 39, and 40, 41 respectively, to close the local or relay-circuits.

In order to control the length of time during which the contact-members 35, 36, are in circuit-closing position, and consequently regulate the length of the blasts of the whistle and horn, as well as the dashes of the recording-instrument, a timed-actuating device is provided for said contact members which will now be described.

A latch 70 is loosely mounted on the rod 30, and rests upon and is slidable along the bottom of the slot 71, in the post 60. The end 72 of the latch 70 is adapted to be engaged by a finger 74, which projects downwardly from the lever 58. A finger 76 projects diagonally upward from the lever 58, and is adapted to be engaged by a finger 78, which projects laterally from the arm 28, 65 when the armature 16 is in attracted posi-

tion, thereby holding the lever 58 in elevated position with the timed-actuating device set in condition to operate.

An escape-wheel 80 is affixed to a shaft 82, journaled at its ends in conical sockets 70 formed in the ends of screws 84, which are threaded through the side-arms 86 of a yoke 88, mounted upon an insulating ledge 90, which projects upwardly from the base 15. A toothed pinion or ratchet-wheel 92 is also 75 affixed to the shaft 82, and is engaged by a toothed pawl 94 pivoted to the end of the lever 58. This pawl is held in engagement with said ratchet-wheel by a coiled spring 96, connected at one end to said pawl and at 80 its other end to said lever. When the lever 58 is swung downwardly by the spring 52, upon retraction of the armature 16 and removal of the prop 78, the pawl 94 causes the ratchet-wheel 92 to rotate, and with it the escape-wheel 80. The speed of rotation of the escape-wheel 80 is controlled by a pallet 98, secured to a shaft 100, journaled at its ends in conical sockets formed in the ends of screws 102, which are threaded through the 90 side-arms 86. A pair of weights 104 are adjustably mounted on arms 106, which are affixed to and project radially from the shaft 100. By adjusting these weights toward or from their center of oscillation, the rapidity 95 of oscillation of the pallet 98 may be varied and consequently the speed of rotation of the escape-wheel 80 and shaft 82. The speed of rotation of the escape-wheel 80 determines the speed of the downward movement of the 100 pawl 94 and lever 58. During downward movement of the lever 58 its finger 74 engages and moves longitudinally the latch 70, and thereby positively moves the movable contact-member out of engagement with the 105 stationary contact-members, but the time consumed in thus moving the movable contact-member is determined by the speed of downward movement of the lever 58.

When the circuit through the magnet-coils 110 10 is closed by the signal-transmitter the armature 16 is attracted; the finger 78 engages the finger 76, and raises the lever 58, and with it the pawl 94; the spring 52 is placed under increased tension; the movable 115 contact-member is moved away from the stationary contact-members, and the end 72 of the latch 70 is disengaged from the finger 74. This is the normal position of the parts, as shown in Fig. 1; the signaling-circuit being 120 closed.

When the circuit through the magnet-coils 10 is broken, the first action of the spring 52 is to swing the armature 16 into its uppermost position, as shown in Fig. 4, and to 125 swing the contact-members 35, 36 into engagement with the stationary contact-members 38, 39, and 40, 41, respectively, to close the local or relay-circuits, and also to bring the end of the latch 70 into engagement with 130

the finger 74. Thereupon the timed-actuating-device immediately commences to operate, that is to say, the spring 52 causes the lever 58 to move downward and thereby 5 actuate the timing-mechanism which is driven by the pawl 94; and as said lever 58 is lowered the finger 74 pushes the latch 70 toward the right, thereby moving the contact-members 35 and 36 away from their 10 stationary coating members to open the local or relay-circuits, and the armature 16 is moved slightly nearer the poles of the magnet, shown in Fig. 5, where it remains until attracted upon energization of the 15 magnet-coils, when said operation may be repeated.

Upon breaks of the controlling-circuit of the relay of long duration, that is to say, of as long or longer duration than the predetermined 20 time of movement of the timed actuating-device the movable contact-member will be positively moved to disengage the stationary contact-members, thereby closing and subsequently opening the local or 25 relay circuit or circuits at the end of a predetermined period of time. Upon breaks of said controlling-circuit of short duration, that is to say, of shorter duration than the predetermined time of movement of the 30 timed actuating-device, the movable contact-member will be positively moved but a short distance by the actuating-spring 52 before the armature 16 is again attracted, whereupon the movable contact-member is positively 35 moved out of engagement with the stationary contact-members and the lever 58 is raised and returned to normal elevated position quickly by the finger 78 engaging the finger 76 and lifting said lever, so that 40 the local or relay-circuit or circuits are closed and subsequently opened in accordance with or for periods of time coextensive with the length of the breaks of short duration.

45 **I claim:—**

1. In a relay, the combination of a relay-magnet, armature, and a circuit-controller for a local circuit, the movable-member of which is responsive to retractive and attractive 50 movements of the armature, respectively to engage and subsequently disengage its fellow member, and a timed actuating-means associated with said movable-member for moving it to disengage its fellow member at the end of a predetermined period of time in case the armature remains 55 retracted, substantially as described.

2. In a relay, the combination of a relay-magnet, armature, and a circuit-controller for a local circuit, the movable member of which is responsive to retractive and attractive 60 movements of the armature, respectively to engage and subsequently disengage its fellow member, and a timed actuating-means associated with said movable-member for moving it to disengage its fellow member at the end of a predetermined period of time in case the armature remains retracted, said 65 means associated with said movable member

arranged to permit such movements of the movable member and also to move said member to disengage its fellow member at the end of a predetermined period of time in case the armature remains retracted, substantially as described. 70

3. In a relay, the combination of a relay-magnet, armature and a circuit-controller, the movable-member of which is moved by said armature to engage and subsequently 75 disengage its fellow member in response to short open-circuit conditions of the controlling-circuit of the relay-magnet, and timed actuating-means associated with said movable-member and arranged to permit such movements of the movable member and also 80 to move said member to disengage its fellow member at the end of a predetermined period of time corresponding substantially with the short open-circuit periods of the controlling-circuit upon the occurrence of a prolonged open-circuit condition of the controlling-circuit, whereby all closures of the circuit controlled by the circuit-controller will be of substantially the same duration, 85 substantially as described. 90

4. In a relay, the combination of a relay-magnet, armature, stationary contact-members, a movable contact-member associated with said armature and movable upon retraction of said armature to engage said stationary contact-members and upon attraction thereof to disengage said stationary contact-members, a timed actuating-means associated with said movable contact-member and arranged to move said member to disengage the stationary contacts at the end 95 of a predetermined period of time in case said armature remains retracted, substantially as described. 100

5. In a relay, the combination of a relay-magnet, pivoted armature, stationary contact-members and a contact-member connected with said armature and movable upon retraction and attraction thereof, respectively, to engage and disengage said stationary contact-members, a timed actuating-device associated with said movable contact-member and arranged to move said member to disengage the stationary contact-members at the end of a predetermined period of time in case said armature remains retracted, substantially as described. 110

6. In a relay, the combination of a relay-magnet, armature, a circuit-controller for a local circuit, the movable-member of which is responsive to retractive and attractive 115 movements of the armature, respectively to engage and subsequently disengage its fellow member, and a timed actuating-means 120 associated with said movable-member for moving it to disengage its fellow member at the end of a predetermined period of time in case the armature remains retracted, said 125 timed actuating-means being reset to nor- 130

mal upon attraction of the armature, substantially as described.

7. In a relay, the combination of a relay-magnet, pivoted armature, stationary contact-members and a contact-member connected with said armature and movable upon retraction and attraction thereof, respectively, to engage and disengage said stationary contact-members, a timed actuating-device associated with said movable contact-member and arranged to move said member to disengage the stationary contact-members at the end of a predetermined period of time in case said armature remains retracted, said movable contact-member having means to engage and restore to normal said timed actuating-device upon attraction of the armature, substantially as described.

8. In a relay, the combination of a relay-magnet, armature, stationary contact-members, and movable contact-member associated with said armature and movable upon retraction of said armature to engage said stationary contact-members and upon attraction thereof to disengage said stationary contact-members, a latch connected with said movable contact-member, timed actuating-means for engaging said latch to move the contact-member bearing it to disengage the stationary contact-members at the end of a predetermined period of time in case said armature remains retracted, said latch permitting attractive movement of the armature independent of the timed actuating-means, substantially as described.

9. In a relay, the combination of a relay-magnet, armature, and retractile spring, a timed actuating-device, and a movable contact-member associated with said armature and timed actuating-device, said member being moved in one direction upon retraction of said armature, and moved for a portion of its travel in the opposite direction by said timed actuating-device and for the remainder of its travel by the attraction of said armature, substantially as described.

10. In a relay, a relay-magnet, armature and retractile spring, a movable contact-member associated with said armature and responsive to a movement thereof in one direction to close a relay-circuit, a pivoted arm arranged for engagement with said contact-member, means to connect said arm with said retractile-spring whereby said spring acts to move said arm to move the contact-member to open the relay-circuit, and means to cause slow movement of said arm during such time, substantially as described.

11. In a relay, a relay-magnet, armature and retractile spring, a movable contact-member associated with said armature and responsive to a movement thereof in one direction to close a relay-circuit, a pivoted arm arranged for engagement with said contact-member to which said retractile spring is

connected, whereby said arm is moved by said spring to move the contact-member to open the relay-circuit, and means to cause slow movement of said arm during such time, substantially as described.

12. In a relay, the combination of a relay-magnet, armature, and a circuit-controller for a local-circuit, the movable-member of which is responsive to retractive and attractive movements of the armature, respectively, to engage and subsequently disengage its fellow-member, and a timed actuating-means associated with said movable-member arranged to permit such movements of the movable-member, and also to move said member to disengage its fellow member at the end of a predetermined period of time in case the armature remains retracted, said timed actuating-means having a spring for operating it which is arranged to be energized by the relay-magnet, substantially as described.

13. In a relay, the combination of a relay-magnet, armature, and a circuit-controller for a local-circuit, the movable-member of which is responsive to retractive and attractive movements of the armature, respectively, to engage and subsequently disengage its fellow-member, and a timed actuating-means associated with said movable-member arranged to permit such movements of the movable-member, and also to move said member to disengage its fellow member at the end of a predetermined period of time in case the armature remains retracted, said timed actuating-means having a normally energized actuator for operating it, substantially as described.

14. In a relay, the combination of a relay-magnet, armature, and a circuit-controller for a local-circuit, the movable-member of which is responsive to retractive and attractive movements of the armature, respectively, to engage and subsequently disengage its fellow-member, and a timed actuating-means associated with said movable-member arranged to permit such movements of the movable-member, and also to move said member to disengage its fellow-member at the end of a predetermined period of time in case the armature remains retracted, said timed actuating-means having its actuator arranged to be energized automatically, substantially as described.

15. In a relay, the combination of a relay-magnet, armature, and a circuit-controller for a local-circuit, the movable-member of which is responsive to retractive and attractive movements of the armature, respectively, to engage and subsequently disengage its fellow-member, and a timed actuating-means associated with said movable-member arranged to permit such movements of the movable-member, and also to move said member to disengage its fellow-member at

- the end of a predetermined period of time in case the armature remains retracted, said 5 timed actuating-means including its actuator being arranged to be reset by the relay magnet, substantially as described.
16. In a relay, the combination of a relay-magnet, armature, and a circuit-controller for a local-circuit, the movable-member of which is responsive to retractive and at- 10 tractive movements of the armature, respectively, to engage and subsequently disengage its fellow-member, and a timed actuating-means associated with said movable-member arranged to permit such movements of the 15 movable-member, and also to move said member to disengage its fellow-member at the end of a predetermined period of time in case the armature remains retracted, said timed actuating-means including its actu- 20 ator being arranged to be reset upon at-tractive movements of said armature, sub-stantially as described.
17. In a relay, the combination of a relay-
- magnet, armature, and a circuit-controller for a local-circuit, the movable-member of 25 which is responsive to retractive and at-tractive movements of the armature, respec-tively, to engage and subsequently disen-gage its fellow-member, and a timed actuating-means associated with said movable- 30 member arranged to permit such movements of the movable-member, and to move said member to disengage its fellow-member at the end of a predetermined period of time in case the armature remains retracted, said 35 timed actuating-means having its actuator arranged to be energized upon the resetting of said actuating-means, substantially as de-scribed.

In testimony whereof, I have signed my 40 name to this specification, in the presence of two subscribing witnesses.
